UNITED STATES PATENT OFFICE.

EDWARD TODD, JR., OF NEW YORK, N. Y., ASSIGNOR TO EDWARD TODD & CO., OF SAME PLACE.

DESIGN FOR A SPOON.

SPECIFICATION forming part of Design No. 28,719, dated May 31, 1898.

Application filed April 16, 1898. Serial No. 677,894. Term of patent 7 years.

To all whom it may concern:

Be it known that I, EDWARD TODD, Jr., a citizen of the United States, residing at New York, in the county of New York and State 5 of New York, have invented and produced a new and original Design for Spoons; and I do hereby declare the following to be a full, clear, and exact description of the same, reference being had to the accompanying drawings, 10 forming a part thereof.

My invention relates to a design for spoons.

In the accompanying drawings, Figure 1 is a front view of a spoon embodying my design. Fig. 2 is a back view of the same. Fig. 3 is 15 an edge view.

The leading or material features of my design consist in a bowl having a certain shape and ornamentation, as hereinafter set forth.

The bowl has an oval shape, being bluntly pointed at one end and provided at the other 20 end with a rounded lug, through which passes the end of the handle. The inner surface of the bowl is decorated with a representation in relief of a birch-bark canoe floating on water which is wave-broken. A paddle lies 25 along the thwarts of the canoe.

Having thus described my design, what I claim is—

The design for a spoon, substantially as herein shown and described. 30

In testimony whereof I affix my signature in presence of two witnesses.

EDWARD TODD, JR.

Witnesses:

L. B. FIEDLER,
JAS. J. FLANNERY.
